DISPENSING HEAD FOR LIQUIDS

Clifford C. Carse, Las Vegas, Nev.
(8880 Kewen Ave., Sun Valley, Calif. 91352)

Filed June 2, 1969, Ser. No. 17,439

Term of patent 14 years

Int. Cl. D23—01

U.S. Cl. D94—3

FIG. 2 is a top plan view thereof; and

FIG. 3 is a bottom plan view thereof.

I claim:

The ornamental design for a dispensing head for liquids, substantially as shown.
